(57) **CLAIM**

The ornamental design for a portion of an article of footwear, as shown and described.

DESCRIPTION

FIG. 1 is a perspective view of a portion of an article of footwear showing my new design;

FIG. 2 is a bottom plan view of the article of FIG. 1.

FIG. 3 is a left side elevational view thereof;

FIG. 4 is a right side elevational view thereof;

FIG. 5 is a front elevational view of the article of FIG. 1; and,

FIG. 6 is a rear elevational view of the article of FIG. 1. The broken lines shown in FIGS. 1–6 immediately adjacent the shaded areas represent the bounds of the claimed design while all other broken lines are directed to environment and are for illustrative purposes only; the broken lines form no part of the claimed design.
